UNITED STATES PATENT OFFICE.

GEORGE A. CARDWELL, OF BROOKLYN, N. Y., ASSIGNOR TO HIMSELF, FREDERICK K. FITCH, OF NEW YORK, N. Y., AND JOSEPH T. MURRAY, OF NEWARK, N. J.

TELEGRAPHIC AND TELEPHONIC INSTRUMENT PROTECTOR.

SPECIFICATION forming part of Letters Patent No. 311,957, dated February 10, 1885.

Application filed February 14, 1884. (No model.)

To all whom it may concern:

Be it known that I, GEORGE A. CARDWELL, of the city of Brooklyn, county of Kings, and State of New York, have invented certain new and useful Improvements in Telegraphic and Telephonic Instrument Protectors; and I do hereby declare the following to be a full, clear, and exact description of the invention.

This invention has for its object the provision and maintenance during its necessity of means for protecting telegraphic, telephonic, and other electrical instruments against injury arising from the introduction into their circuits of abnormally-powerful currents of electricity.

My invention consists of an electrical apparatus designed to be placed in circuit with the instruments to be protected, and of such nature and construction as not to be affected or energized by the normal operating-current; but when a powerful current is accidentally introduced—as, for instance, by the line-wires coming in contact with wires conducting currents for electric lighting—the apparatus will be so operated as to immediately break the circuit of the working instruments and ground the dangerous current. The apparatus is also so arranged that it will automatically restore the circuit to its normal condition when the dangerous current has been eliminated.

The drawing represents a top view of the apparatus, partly in section, showing the construction and arrangement of the several component parts. Upon an ordinary base, A, are secured two electro-magnets, N and M, with their armatures *n* and *m* hinged, respectively, at *r* and *r'*. *n*² and *m*² are the cores of the magnets, and *n*³ and *m*³ are the outside extensions of the iron core. The armatures *n* and *m* have each at their inner ends a short piece of metal, *n'* *m'*, separated by strip of insulating material *x* *x'* from the main piece of the armature. The armature *n* is provided with the back contact-point, *c'*, and the armature *m* with the back contact-points, *c* and *c*'. *c* and *c'* are kept in contact with the ends of the adjusting-screws *t'* and *t*³ by the retractive force of the springs *s* *s'*, which are attached to the armatures and to adjusting-screws F F, working in suitable pieces secured to the base. These screws al-

low of the graduation of the strength of the 50 springs according to the strength of the current normally passing through the line. The springs must be of such strength that the armatures will not be drawn toward the magnets except when energized by currents much more 55 powerful than the working current of the line. The adjusting-screws *t'* *t*³ work in angle-pieces secured to the base-plate, the same pieces also carrying binding-posts T T', to which are attached the wires *t* *t'*, connecting with the instruments which it is desired to protect. Between the two electro-magnets a metal plate, E, is secured, having a binding-post, G, directly connected with ground. In the upper part of the plate E three screws, *o*² *i*² *d*², work. 60 These screws are respectively opposite the contact-points *o* on the lower side of the insulated end *n'* of the armature *n*, the contact-point *i* on the spring *h*, and the contact-point *d* on the lower side of the armature *m*. 70

When the instrument is not in use, or the current is normal, the contact-point *i* is almost, but not quite, in contact with the platinum point of screw *i*², the contact-point *o* is a little farther separated from the screw *o*², and the contact-point *d* is still more widely separated. Screws are used, so that these points may be kept in correct adjustment. 75

The wire used in winding the magnet M is in two sections—fine wire W and coarse wire 80 *w*. The fine wire is wound in the usual manner next to the soft-iron core, and is for the purpose of energizing the magnet more quickly than if the magnet were composed of coarse wire only. The other section, which is not 85 continuous with the first, but composes a part of the same circuit, is wound with very coarse wire. Both these coils or part of a coil of electro-magnet M are in the normal circuit. The instrument or instruments to be protected are 90 inserted between them—that is, they are each connected to the instruments in such a way that the normal current passes through one part of this double coil, then through the instruments, and finally through the other part 95 of the double coil. When an abnormal current enters the line, it for an instant pursues the same course; but almost immediately the

fine-wire part of the coil is cut out and the current passes entirely through the large wire.

To the binding-posts L L' are attached the line-wires l l'. The core of magnet N is surrounded with coarse wire only, wound in the usual manner. It is brought into use only when the abnormal current enters at L'. The contacts at i and e are made by the screw i² and a platinum contact-point on m' and two opposite points attached to a small spring-plate, K, secured to the block k, which is insulated. At e the points are normally in contact, while at i they are slightly separated.

The connections are as follows: One of the line-wires enters the binding-post L'. This binding-post is connected to one end of the coil of the electro-magnet N. The other end of this coil is connected with the insulated end n' of the armature n. This in turn is connected by a covered wire with the insulated end m' of armature m. The line-wire entering at binding-post L is connected with the outside of the coarse-wire coil of electro-magnet M. The other end of this coil is attached to the armature m. A connection is made between the binding-post L' and the inner end of the fine-wire coil of M. The outer end of the fine-wire coil is connected with the armature n. The binding-post G connects with ground. The instruments are connected by means of binding-posts T and T'. The normal circuit is beginning at L through the coarse wire of magnet M to armature m through contact e to T, thence through the instrument or instruments to be protected to T', and on through contact e', armature n, to the fine wire of magnet M, thence to line through post L'. Should a powerful current gain access to the line, and enter the apparatus at L, magnet M is instantaneously energized. Armature m is drawn down, the contact at e is broken, cutting out line-instrument, the contact at d is made, and ground-circuit completed. As soon as circuit is closed the coarse wire of M takes the whole abnormal charge direct to earth by way of m d d' G², &c. When the line is relieved, m is drawn back by the spring s, contact e is closed, and the line is again in normal condition. Should the heavy current enter the apparatus from the opposite direction at L', it energizes the magnet M by entering the fine-wire section by means of the wire b, and operates the armature m, as before. The contact at e is broken, the contact at i on the spring K is made. The breaking of the contact e cuts out the magnet M, demagnetizing it, and of course releases the armature m, which in receding closes the contact e on the spring K before the contact i is bro-

ken, forming a temporary ground-circuit through magnet N, insulated end n' of armature n, contact at e, between spring K and insulated end m' of armature m, contact at i, between spring K and screw i², attached to ground-plate E, and ground-plate E to ground. The current now passing through N energizes it, and draws down the armature n and forms a direct ground-circuit through n', contact o, and ground-plate E.

By the use of my device the entire abnormal current is diverted to ground. In most of the instruments in use the current divides, a portion going over the line, though the larger part goes to ground.

Having now fully described my invention, 75 what I claim, and desire to secure by Letters Patent, is—

1. In an electro-magnetic device for protecting electrical instruments from abnormal currents, two electro-magnets, one wound with 80 coarse wire only and not normally in circuit, the other wound with two separate non-continuous superposed coils, one of fine wire and the other of coarse wire, but both coils in the same normal circuit, the instruments to be 85 protected being interposed between the coils or parts of a coil, substantially as shown and described.

2. In an electro-magnetic device for protecting electrical instruments from abnormal currents, 90 conducting-armatures of two electro-magnets having insulated ends electrically connected but mechanically independent, substantially as shown and described.

3. In an electro-magnetic device for the protection of electrical instruments from abnormal currents, an insulated independent spring, K, having two contact-points, one, e, normally in contact with the insulated portion m' of an armature, m, of an electro-magnet in the 95 normal circuit, while the other, i, is separated from the ground contact-point by a slight interval, substantially as shown and described.

4. In an electro-magnetic apparatus for protecting electrical instruments from abnormal 105 currents, the combination of electro-magnet N, electro-magnet M, with two coils, one of fine and the other of coarse wire, the armatures n and m, having insulated metallic ends n' and m', retracting-springs s s', spring K, 110 ground-plate E, and contact-points e, e', e, i, and d, substantially as shown and described.

In witness whereof I have hereunto set my hand.

GEORGE A. CARDWELL.
